UNITED STATES PATENT OFFICE.

ALFRED P. SEIDELL, OF BLOOMFIELD, NEW JERSEY, ASSIGNOR TO ORANGE LIGHTING FIXTURE MANUFACTURING CO., A CORPORATION OF NEW JERSEY.

DESIGN FOR A LIGHTING-FIXTURE HUSK OR SIMILAR ARTICLE.

Application filed February 5, 1927. Serial No. 20,623. Term of patent 7 years.

To all whom it may concern:

Be it known that I, ALFRED P. SEIDELL, a citizen of the United States, and a resident of Bloomfield, county of Essex, and State of New Jersey, have invented a new, original, and ornamental Design for Lighting-Fixture Husks or Similar Articles, of which the following is a specification, reference being had to the drawing, forming a part shown hereof.

In these drawings:

Figure 1 shows a perspective view of the lighting fixture husk or similar article; and

Figure 2 is a diagrammatic sectional view of the same for the purpose of showing contour.

I claim:

The ornamental design for a lighting fixture husk or similar article substantially as shown.

ALFRED P. SEIDELL.
